V. H. HALLOCK.
Damper-Regulator for Steam-Boilers.

No. 222,489.

Patented Dec. 9, 1879.

Fig. 1.

UNITED STATES PATENT OFFICE

VALENTINE H. HALLOCK, OF BROOKLYN, NEW YORK.

IMPROVEMENT IN DAMPER-REGULATORS FOR STEAM-BOILERS.

Specification forming part of Letters Patent No. **222,489**, dated December 9, 1879; application filed October 30, 1879.

To all whom it may concern:

Be it known that I, VALENTINE H. HALLOCK, of Brooklyn, in the county of Kings and State of New York, have invented a new and useful Improvement in Damper-Regulators for Steam-Boilers; which improvement is fully set forth in the following specification, reference being had to the accompanying drawings, in which—

Figure 1 shows my apparatus partly in side view and partly in section. Fig. 2 is a plan or top view of the same.

Similar letters indicate corresponding parts.

This invention consists in a regulator of certain novel construction for attachment to a steam-boiler, whereby the damper in the smoke-flue is set according to the pressure of the steam to regulate the draft, as hereinafter fully described, and pointed out in the claims.

In the drawings, the letter A designates a cylinder, which is held in a vertical position upon a bracket, B, secured to a post, C, or to the wall. This cylinder A receives steam from the boiler to which the apparatus is applied, and in the same works a plunger or piston, D, the latter being inserted into the cylinder through its upper end, where the cylinder is provided with a packing-ring, a.

The letter E designates a damper, which is arranged in a flue, F, serving to carry off the smoke from the furnace of the boiler. To the pivot of this damper E and externally of the flue F is secured a segment, b, to which is fastened one end of a cord or chain, c, which runs over a pulley, d, and the other end of which is fastened to a stem rising from the plunger D. In this manner the damper E connects with the plunger D, and their arrangement is such that when the plunger is in a lower position the damper is open, as shown. To the segment b is also fastened one end of a cord or chain, e, which runs over a pulley, f, and to the other end of which is fastened a weight, g, or a spring.

The plunger D is adapted to balance a certain pressure of steam—say, fifty pounds—and it remains inactive when the pressure remains below that point. When, however, the pressure of steam rises the plunger D is thereby

forced upward and the cord c is slackened, so that the segment b may follow the action of the weight g, which is to turn the segment and thereby close the damper. By this means the draft through the boiler-furnace is retarded and the fire is lowered, so that the pressure of steam falls, and when this has taken place the plunger D returns to a lower position, and the segment b is moved back by the tension of the cord c to reopen the damper.

The plunger D may be arranged to resist or balance a fixed pressure of steam by its inherent gravity; but I prefer to use weights H for this purpose, in order that the power of the plunger may be increased or diminished at will. These weights H are suspended from the plunger D by a frame consisting of cross-heads i and connecting-rods j.

As the plunger D rises and descends with the rise and fall of the steam-pressure, it is expedient or desirable to gradually increase and lessen the weight thereof, in order that the damper E may not be suddenly closed or opened. To this end I connect with the plunger D a self-adjusting weight, K, consisting, in this example, of a chain, which is linked to the weight-frame i j, and which partially or wholly rests on the ground or floor when the plunger is in a lower position. When the plunger D rises the chain-weight K is thereby gradually lifted from the floor, and the power or resistance of the plunger is increased to a corresponding degree, while when the plunger descends said weight takes its place on the floor, link by link, and a corresponding load is taken off the plunger.

For the purpose of supplying the cylinder A with steam, I make use of a feeder, L, which communicates with the cylinder at or near the bottom through a pipe, m, having a suitable stop-cock, and from the top of which extends a pipe, n, to connect with the boiler. The live steam entering the feeder L condenses and cools off, and the condensed steam enters the cylinder A under the pressure of the live steam through the pipe m. The advantage gained by this arrangement is that the cylinder A remains cool and the packing-ring a is not liable to be affected by the steam; but it

is obvious that the feeder may be omitted and the live steam conducted directly to the cylinder, so as to act directly on the plunger.

What I claim as new, and desire to secure by Letters Patent, is—

1. The combination of a steam-cylinder, a plunger working in the cylinder, a self-adjusting weight acting on the plunger, a damper connecting with the plunger, and a weight or spring connecting with the damper, all adapted to operate substantially as described.

2. The combination of a steam-cylinder, a

weighted plunger working in the cylinder, a feeder communicating with the cylinder, a damper connecting with the plunger, and a weight or spring acting on the damper, all adapted to operate substantially as described.

In testimony that I claim the foregoing I have hereunto set my hand and seal this 20th day of October, 1879.

VALENTINE H. HALLOCK. [L. S.]
